ATTORNEY

UNITED STATES PATENT OFFICE.

ROMAN SCHOEPKE, OF WILKES-BARRE, PENNSYLVANIA.

FOOD CONTAINER.

Application filed October 28, 1926. Serial No. 144,668.

The main object of this invention is to provide a container which is conveniently separated into compartments with the aid of auxiliary bottoms and may be readily 5 opened on either end without disturbing the remaining compartments. This container is useful to manufacturers of various products which are allied to each other, in which case the compartments of the container may be 10 filled with dissimilar products which may be opened separately as occasion may require.

Another object is to provide a container having a plurality of compartments which 15 may be opened at opposite ends of the container and may be filled with a fluid or a solid, according to the type of container used.

The above and other objects will become 20 apparent in the description below, in which characters of reference refer to like-named parts in the drawing.

Referring briefly to the drawing, Figure 25 1 is a vertical sectional elevational view of one type of container suitable for fluids.

Figure 2 is an enlarged sectional elevational view, showing the method of securing the container sections together.

Figure 3 is an enlarged sectional elevational view, showing the means of joining the covers to the edges of the container sections.

Figure 4 is a vertical sectional elevational view of the type of container used for solids.

Figure 5 is an enlarged sectional elevational view, showing the means of positioning the false bottom in the type of container shown in Figure 4.

Referring in detail to the drawing, Figure 1 illustrates one type of container suitable for use of fluids. This container consists of two cylindrical sections 10 and 11 which are joined at their adjacent edges by a joint. These cylindrical sections are separated by a false bottom 12 and are capped by covers 13 and 14. The opposing edges of the cylindrical sections 10 and 11 are spun and formed into a down-turned edge 15 which is spaced-apart from the surface of the sections 10 and 11. In the space between the down-turned edge 15 and the surface of the sections 10 and 11, a ledge 16, extending from a rim 17 of the cover members 13 and 14, is inserted. The joints so formed when pressed tightly and soldered 55 form a leak-proof joint which is compact

in formation. The false bottom 12 separating the container sections into two compartments, an upper 18 and a lower 19, has a larger diameter than the diameter of the 60 container sections 10 and 11. The portion 20 of this false bottom which extends beyond the periphery of the container sections is bent upwardly and then turned down at 21, as illustrated in Figure 2, with a space 65 equal to double the thickness of the material used between the down-turned portion 21 and the inclined area 20. The lower edge of the upper cylindrical section 10 is turned upwardly and angularly outward, as 70 indicated by the numeral 22 and its edge is inserted into the space between members 20 and 21 of the false bottom. The upper edge of the cylindrical section 11 is wrapped about the outer surface of the portion 21, 75 an up-turned lip 24 is formed which also is inserted into the remaining portion of the space between members 21 and 20 of the false bottom. This joint when formed is also pressed together to make a more compact joint and is then soldered to seal the 80 container sections.

Figure 4 illustrates the type of container used for the storing of all solids other than liquids. This container consists of a cylindrical section of metal 25 which is deformed inwardly intermediate its width by creating a channel 26. Closing up this container forms an internal shelf 27 upon which a false bottom 28 having an up-turned rim 29 85 is seated. This false bottom 28 separates the container into two compartments 30 and 31. The open ends of the cylindrical section 25 are closed by covers 32 and 33 which are provided with down-turned rims 34 90 which slip over the periphery of the cylindrical section and close the container compartments.

The invention consists of two types of containers, one of which is more inexpensive 100 than the other to manufacture. Both containers may be conveniently used for storing fluids or solids. The inexpensive container, illustrated in Figure 4, consists of a single cylindrical section 25, separated intermediate its length by a false bottom 28, which is mounted on a shelf 27. The covers 32 and 33 closing this container may be slipped from place to uncover either of the compartments 30 or 31 when emptying either of the same without disturbing the remaining compartments. The container 105 110

illustrated in Figure 1, consists of two cylindrical sections closed at their adjacent ends by a false bottom which is positioned in place by a joint, illustrated in Figure 3.

5 It is to be noted that certain changes in form and construction may be made without departing from the spirit and scope of the invention.

I claim:

10 A container comprising a pair of cylindrical sections placed end to end, a false bottom positioned between said sections, the edges of said sections and false bottom

being interlocked, and covers interlocking with the opposing edges of said sections 15 closing said containers, said false bottom dividing said container into an upper and lower section, said false bottom having a larger diameter than the cylindrical sections and being turned angularly upward, the adjacent edges of said sections being turned angularly upward and being interlocked with the up-turned edge of the false bottom. 20

In testimony whereof I affix my signature.

ROMAN SCHOEPKE.
